US00D681874S

(12) **United States Design Patent**
Maxik et al.

(10) **Patent No.:** US D681,874 S
(45) **Date of Patent:** ** May 7, 2013

(54) **POLE FOR A STREET LIGHT LUMINAIRE**

(75) Inventors: **Freddie S. Maxik**, Indialantic, FL (US); **David Henderson**, Indialantic, FL (US); **Eric Bretschneider**, Clarkston, MI (US); **Addy S. Widjaja**, Palm Bay, FL (US); **Kenneth Marion Bowen**, Indian Harbor Beach, FL (US); **Jean Sundin**, New York, NY (US); **Enrique Peiniger**, New York, NY (US)

(73) Assignees: **Lighting Science Group Corporation**, Satellite Beach, FL (US); **Office for Visual Interaction, Inc.**, New York, NY (US)

(**) Term: **14 Years**

(21) Appl. No.: **29/404,856**

(22) Filed: **Oct. 26, 2011**

Related U.S. Application Data

(62) Division of application No. 29/356,102, filed on Feb. 19, 2010, now Pat. No. Des. 650,519.

(57) **CLAIM**

We claim, the ornamental design for a pole for a street light luminaire, as shown and described.

DESCRIPTION

FIG. 1 is a side elevational view of the invention, with the opposite side being a mirror image thereof;

FIG. 2 is a top plan view of the invention;

FIG. 3 is a bottom plan view of the invention;

FIG. 4 is a front elevation view of the invention;

FIG. 5 is a rear elevation view of the invention; and,

FIG. 6 is a perspective view of the invention.

The phantom lines shown in FIG. 1-FIG. 6 are environmental and not part of the claimed design.

References to "side", "top", "front" and "rear" in the figure descriptions are not meant to require certain in-use orientation, a pole for a street light luminaire according to the claimed design may be used in any orientation.
